UNITED STATES PATENT OFFICE

FRED PASS, OF CHICAGO, ILLINOIS, ASSIGNOR OF ONE-HALF TO GEORGE D. NORTON,
OF TOLEDO, OHIO

KNIFE SHARPENER

Application filed November 22, 1926. Serial No. 149,912.

This invention relates to sharpening devices, and more particularly to a draw knife sharpener of that general type in which the blade of the knife is moved in contact with a cutting edge so as to scrape off or remove a portion of the material of the blade for sharpening the same.

In devices of this character with which I am familiar, the cutting edge which the knife blade is moved in contact with, is disposed at right angles to the blade, that is, in parallelism with the wall of the guiding slot with which the blade contacts during movement thereof through the slot. By having the cutting edge arranged in this manner, the material removed from the knife blade is scraped or torn off of the blade and is not cut therefrom. This results in producing a very ragged edge on the knife blade while rendering the use of the sharpening device unnecessarily hard. I have found that by properly relating the cutting edge of the device and the grooves which receive the knife blade, it is possible to produce a device in which the material is cut neatly from the blade with a shearing cut so as to quickly produce a sharp, smooth edge which is free of all raggedness or unevenness. This greatly facilitates the sharpening of a knife and also avoids the objection inherent in devices of this sort now in use, that an unnecessary amount of the metal of the knife blade is torn away before a satisfactory cutting edge can be produced.

One of the main objects of my invention is to provide a device of the character stated of simple and inexpensive construction which avoids the objections above noted incident to sharpeners of this general type now in common use. A further object is to provide a device of this character by means of which a smooth, sharp cutting edge can be quickly produced on a knife blade with very little effort. Another object is to provide a cutting member or plate for acting upon the blade of the knife, this plate having a plurality of cutting edges and being adjustable to expose different portions of these edges, the blade being also reversible to bring different edges into operation. Further objects will appear from the detailed description.

In the drawings:

Figure 1 is a perspective view of a knife sharpener constructed in accordance with my invention;

Fig. 2 is a back view of the sharpener;

Fig. 3 is a section taken substantially on line 3—3 of Fig. 2;

Fig. 4 is a section taken substantially on line 4—4 of Fig. 2;

Fig. 5 is an elevation of a modified form.

The sharpener includes a body or block 1 of rectangular shape which may be formed of any suitable or preferred material, such as cast iron or steel. This body is provided in its front face with a central longitudinally extending groove 2 of elongated rectangular shape and with two slots 3 extending from the lateral edges thereof and converging toward the groove 2. As will be noted more clearly from Fig. 4, these slots also converge toward the front face of the block. A suitable handle 4 extends from one end of block 1, this handle being formed of a suitable length of heavy wire or other suitable material which is bent to provide the substantially parallel arms 4A the ends of which are secured to the block in any suitable manner as by having the material of the block cast about the arm, though any other suitable or preferred means for securing the handle to the block may be employed. It will also be evident that the handle can be of any other suitable shape or construction than that shown and described.

A rectangular cutting plate 5 is mounted in groove 2 of block 1. This plate is formed of highly tempered steel of sufficient hardness to readily cut tempered steel such as is commonly employed for knife blades and similar purposes. Plate 5 fits snugly within groove 2 and is removably secured therein by means of a bolt 6 passing through the plate centrally thereof, this bolt extending through a slot 7 extending through the block 1 from the bottom of groove 2, a suitable washer 8 being disposed about the bolt 6 and confined between the back of the block and a nut 9 threaded on to the bolt. This provides simple and efficient means whereby the cutting plate 5 is secured in position in the

groove 2 and can be readily adjusted longitudinally thereof. It will also be noted that by removing bolt 6 the plate can be readily removed and reversed in the groove. The 5 lateral edges of the plate 5 extend across the inner end portions of slots 3 and by adjusting this plate longitudinally of groove 2 the entire length of the cutting edge at each side of the plate can be brought into position to 10 operate upon the knife edge. As soon as any one portion of the cutting edge of the plate becomes too dull for satisfactory service, the plate can be adjusted slightly in proper direction to expose an unused portion of the 15 edge for use. It will thus be seen that the sharpener can be kept at all times in the very best condition for quickly sharpening knives and similar tools.

As will be noted more clearly from Fig. 4, 20 plate 5 is of appreciable thickness and each lateral edge or face 10 thereof is flat and disposed at right angles to the plane of the plate. This provides at each side of the plate front and back cutting edges 10A and 25 10B, respectively. Due to the fact that the slots 3 are disposed at an inclination towards the front of the block, the lower or outer wall 3A of each slot is disposed at an acute angle to the cutting edge 10A of plate 30 5. It will thus be seen that the blade of a knife inserted through slot 3A will be disposed at an acute angle to the cutting edge 10A considered from front to back of the blade, and will also be disposed at an inclination 35 to the cutting edge downwardly and inwardly of the block 1 toward the groove 2. This insures that, as the knife blade is drawn through the slots 3 from the front toward the back of block 1, the cutting edge 10A will 40 exert a shearing effect on the blade so as to smoothly cut or shear off the material at the lower edge of the blade at one side thereof. As there is no pulling or dragging incident to this shearing off of the metal, the knife 45 blade can be quickly drawn through the device with little effort. By drawing the blade through slots 3 alternately the metal at opposite sides of the blade is sheared off so as to quickly produce a cutting edge. This 50 cutting edge is produced with a minimum of effort and is smooth and sharp, being free of all raggedness or unevenness due to the fact that the cutting edges 10A exert a true cutting effect for removing the metal of the 55 blade and the metal is not removed by being pulled or torn off of the blade as in sharpening devices of this character now in use with which I am familiar.

In the event that the portions of cutting 60 edge 10A extending across the slots 3 become dull to such an extent as not to give satisfactory service, the plate 3 can be adjusted slightly in either direction so as to expose an unused part of the edge 10A and position it 65 across the slots. The slot 7 in block 1 is of

proper length to permit the plate 5 to be used for substantially its full length. After the front cutting edges 10A have been used to such an extent as to be rendered too dull for satisfactory service for their full length, the 70 blade can be removed and reversed so as to expose the unused cutting edges 10B. In this connection, it will be noted that the rear cutting edges 10B do not contact with the knife blade during the sharpening operation, 75 as will be clear by reference to Fig. 4. The block 1 and handle associated therewith are, barring accident, practically indestructible and I therefore contemplate furnishing the cutting plate 5 separately in order that a dull 80 plate may be replaced when all of the cutting edges thereof have been used.

In Fig. 5 I have shown a modified form in which the block 2A is mounted at an inclination on a suitable base 11 which may be 85 formed integrally with the block. This base provides means whereby the device can be secured upon a table, draining board, or other suitable support, indicated by S.

In either form of the device, the knife blade 90 is inserted in the slots 3 and moved through the same from front to back of block 1, as will be readily understood from Fig. 1. The shearing effect of cutting edge 10A for removing the metal of the blade can be somewhat increased by inclining blade b of the knife downwardly and forwardly of block 1, as indicated, although I do not consider this essential as a very effective shearing 95 effect is produced by having the slots 3 inclined in two directions to block 1 and related to the cutting edge of the blade in the manner set forth.

I also contemplate making the sharpener with one slot only. In this modification the 105 knife can be readily sharpened by drawing the blade thereof through the slot, in contact with the cutting edge, the direction in which the blade is drawn being alternately reversed. When using the form which is unsecured and is provided with a handle, the sharpener is held in position adjacent a suitable support with the lower end of the block bearing firmly on the support, as will be readily understood.

What I claim is:—

1. A sharpening device of the character described comprising a block of substantial thickness, a sharpening member mounted on the block, there being a narrow slot having parallel walls in the block extending to the sharpening member, the block being of such thickness that the walls of the slot are relatively wide whereby the slot serves to guide and maintain an article to be sharpened at the proper angle against the sharpening member.

2. A sharpening device of the character described comprising a block of substantial thickness, a sharpening member mounted on the block, said block being provided with a

pair of narrow slots converging toward and extending to the sharpening member in two planes at an angle to one another, the walls of each slot being parallel and the block being of such thickness that the walls of the slots are relatively wide whereby each slot serves to guide and maintain an article to be sharpened at the proper angle against the sharpening member.

3. A sharpening device of the character described, comprising a block having a longitudinally extending groove, a sharpening member mounted in said groove for adjustment therein, there being a longitudinal slot extending through the block and in said groove, and narrow slots extending from the opposite sides of the block and converging toward the groove in two planes, a bolt passing through the sharpening member and the longitudinal slot and a nut on the end of the bolt, serving to clamp the sharpening member in adjusted position, the two side walls of each of the narrow slots being relatively wide so as to form guides to maintain the article to be sharpened at the proper angle against the sharpening member.

4. A sharpening device of the character described, comprising a block having a longitudinally extending groove, a sharpening member mounted in said groove for adjustment therein, there being a longitudinal slot extending through the block and in said groove, and narrow slots extending from the opposite sides of the block and converging toward the groove in two planes, a bolt passing through the sharpening member and the longitudinal slot and a nut on the end of the bolt, serving to clamp the sharpening member in adjusted position, the two side walls of each of the narrow slots being relatively wide so as to form guides to maintain the article to be sharpened at the proper angle against the sharpening member, and a handle secured to said block, said handle including two parallel arms, the outer ends of which are joined together and the inner ends of which are secured to the block.

In witness whereof, I hereunto subscribe my name this 20th day of November, 1926.

FRED PASS.
